UNITED STATES PATENT OFFICE

ROBERT HENRY DAVIS, OF LONDON, ENGLAND

DIVING APPARATUS

Application filed July 19, 1929, Serial No. 379,502, and in Great Britain October 3, 1928.

This invention relates to improvements in diving apparatus and has for its object to provide means whereby a diver can undergo the usual decompressing process under comfortable conditions free of the water instead of its being effected under water in the usual way.

According to the present invention there is provided apparatus for transporting divers which comprises a chamber having disposed at the lower end thereof an entrance, adapted to be lowered to a predetermined level in water, means either within or externally of the chamber for supplying the said chamber with compressed air, means for closing the entrance after a diver has passed into the chamber from the water, and means for gradually reducing the air pressure within the said chamber.

In a suitable arrangement for carrying the invention into effect, the chamber is provided with an entrance door and an exit door both of which open inwardly, so that excess of internal pressure over external pressure presses them on to their seatings, and these two doors, preferably hinged, are arranged one in the floor of the chamber permitting the diver to pass into the chamber when under water, and the other door in the top or side of the chamber permitting the diver's exit from the chamber when above water.

To enable the invention to be fully understood the same will be described by reference to the accompanying drawing, which is a sectional elevation of a diving chamber constructed in accordance with the invention and showing it in use.

Referring to the drawing, *a* is the closed chamber, which is shown as of upright cylindrical form, and comprises a cylindrical wall *b* and a top and floor *c*, *d*, respectively. *e* and *f* are two hinged doors arranged, respectively, in the top *c* and the floor *d*, and designed to bear against seatings thereon when both doors are closed and arranged to open inwardly, so that excess of internal pressure over external pressure presses the doors tightly on to the said seatings. Suitable means, such as screws, are employed for se-

curing the said doors *e* and *f* in the closed position.

g is a flexible tube connected between the chamber *a* at *h* and an air supply on a diving vessel on the surface of the water, for supplying compressed air to the said chamber, and *i* is a cable containing leads for telephonic communication between the chamber and the said vessel on the surface of the water and for the supply of electricity therefrom for lighting and other purposes.

j is a cylinder of compressed oxygen, or other suitable respiratory gas for supply to the diver, as hereinafter described. *k* and *l* are depth and pressure gauges respectively, and *m* is a movable ladder. *n* is the shot-rope of the diver extending through guide-eyes *o*, *o* on the chamber *a*.

The chamber *a* with, or without, an attendant A inside it and with the door *f* open and the ladder *m* placed so as to depend from the entrance in the floor *d*, is lowered in the water to a predetermined level representing the diver's first decompression stage, air being supplied to the chamber at a pressure sufficient to keep the same free of water at whatever depth the chamber may be submerged.

The diver B, on his ascent by the rope *n* climbs the ladder *m* and enters the chamber *a* through the lower doorway, his air-pipe *p* and telephone cable *q* connection being disconnected. In the case of the diver wearing a self-contained type of diving dress, there is, of course, no air-pipe to the surface to be disconnected. The ladder *m* is then lifted into the chamber *a* and the door *f* closed and the said chamber *a* is raised and placed on board the diving vessel where the process of decompression is completed in comfort.

It will, of course, be understood that the moment the diver reaches the chamber *a*, the first stage of the decompression period begins.

To accelerate the expulsion of nitrogen from the diver's body after working at great depths, and so shorten the decompression time, the diver may breathe oxygen, or other suitable gas, by way of a breathing apparatus, not shown, connected to the cylinder *j*.

After the decompression is completed, the

diver leaves the chamber preferably by the upper door *e* through the medium of the ladder *m*.

Although the exit door *e* has been described as being arranged in the top *c* of the chamber *a* it is to be understood that it may be arranged in the side wall *b* of the said chamber.

It will of course be understood that immediately the diver enters the chamber *a* and either before or after the door *f* is closed, he may be divested of his dress without delay and can receive hot drink and food.

From the foregoing it will be seen that the diver after returning to the chamber, commences immediately to decompress and can be drawn as rapidly as is practicable to the surface where the process of decompression can be completed conveniently and without discomfort and without regard to weather conditions. The diver is thereby protected from unnecessary exposure to cold water and from the monotony of the usual lengthy decompression stages, the decompression being carried out mainly at the surface under comfortable conditions.

25 I claim.

Apparatus for transporting divers to the surface from the first decompression stage of an ascent, which comprises a chamber adapted to be lowered to the first decompression stage of a diver in water and having in the floor thereof an entrance for a diver, means for supplying the chamber with a sufficiency of air at the pressure prevailing at the depth of the first decompression stage to prevent the chamber when lowered from becoming flooded with water, a door opening inwardly for closing said entrance after the diver has passed into the chamber from the water, means for gradually reducing the air pressure within said chamber to normal atmospheric pressure after closure of the entrance door and at least one exit in the structure of the chamber above the floor thereof, and a door for said exit arranged to open inwardly.

ROBERT HENRY DAVIS.
